US0D1055010S

(12) **United States Design Patent** (10) Patent No.: **US D1,055,010 S**
(45) Date of Patent: ** Dec. 24, 2024

(54) **TELEVISION RECEIVER**

(71) Applicant: **LG ELECTRONICS INC.**, Seoul (KR)

(72) Inventors: **Jiwon Park**, Seoul (KR); **Yongseok Kim**, Seoul (KR)

(73) Assignee: **LG ELECTRONICS INC.**, Seoul (KR)

(**) Term: **15 Years**

(21) Appl. No.: **35/519,528**

(22) Filed: **Nov. 10, 2023**

(80) **Hague Agreement Data**

Int. Filing Date: **Nov. 10, 2023**

Int. Reg. No.: **DM/233919**

Int. Reg. Date: **Nov. 10, 2023**

Int. Reg. Pub. Date: **Dec. 29, 2023**

(30) **Foreign Application Priority Data**

Jun. 22, 2023 (KR) 30-2023-0024049

(51) **LOC (14) Cl.** **14-03**

(52) **U.S. Cl.**

USPC **D14/126**
